UNITED STATES PATENT OFFICE.

CHARLES ROSS, OF BLAIR, NEBRASKA.

ADJUSTABLE OPEN-TOP HORSE-COLLAR.

1,397,743.

Specification of Letters Patent. Patented Nov. 22, 1921.

Application filed October 12, 1920. Serial No. 416,548.

To all whom it may concern:

Be it known that I, CHARLES Ross, a citizen of the United States of America, residing at Blair, in the county of Washington and State of Nebraska, have invented certain new and useful Improvements in Adjustable Open-Top Horse-Collars, of which the following is a specification.

My invention relates to improvements in 10 horse collars that are openable at the top for application and adjustment to a horse's neck and shoulders. While it may be advantageously applied with any style of open topped horse-collar, this contrivance 15 is believed to perform its most beneficial functions when used in combination with horse-collars of the sweeny type, shown and described in my Patent No. 981,006, January 10, 1911, horse collar.

20 One of the objects of this invention, is to supplement the lateral or width adjustment, which in collars of this full flexible sweeny type is attained by the applied hames with their top and bottom straps or 25 other couplings, by also using a vertical or longitudinal adjustment. Such length adjustment is particularly desired to meet the varied conditions of any individual horse at different seasons of the year, as well as 30 the changes occurring during the growth of young immatured animals.

Another object is to further extend and increase the length and lateral pliability of the opposed top ends of the sides of the 35 sweeny type of collar, without increasing the transverse flexibility, that is, forward and backward, at the vertex of the coupled adjusted and arched top; and to provide efficient permanently attached means to 40 overcome the tendency of the tops of the hames and their coupling, to drift forward out of the exterior groove between the fore-wale and after-wale of the collar in this top of increased length and lateral flexibility.

45 A further object is the attainment of a permanently attached efficient weather cap or housing-plate, well ventilated, automatic in its application at any adjustment of the vertex of the arched collar top and without 50 additional expense over the requisite outlay to attain the other desirable features.

These and other minor structural objects hereinafter more clearly set forth, and the novel elemental features of which are re-

cited in the finally appended claims, I have 55 attained by the means and mechanism illustrated in the accompanying drawings in which—

Figure 1, is a longitudinal section through the after-wale of a fractional top portion 60 of such a collar, coupled at its position of largest adjustment and the view taken on the broken line 1 of Figs. 2 and 4; Fig. 2, a fragmental transverse section of the attached extension cap, taken on the broken 65 lines 2 and 3 of Figs. 1 and 3; Fig. 3, a perspective top and front view of the permanently connected parts of the collar, opened at the top and the ordinary inner pressed leather chafing or top-pad removed; Fig. 4, 70 a perspective front and top view of the complete assembled collar, closed to its smallest adjustment with the inner top or neck-pad attached; Fig. 5, a front elevation of the collar, all the parts complete and as 75 assembled with the regular pressed-leather inside neck-pad applied and the collar adjusted to its smallest size; Fig. 6, a back elevation of the collar as adjusted in Fig. 5; and Fig. 7, is a view similar to Fig. 6, with 80 the pressed leather chafer or inner neck-pad omitted. In all of these views similar reference numerals denote like parts and the arrow heads indicate the direction in which the section views are taken. 85

In the construction of the previously patented horse collar, mentioned above, a throat part and the sweeny parts or tops of the sides are stuffed with short fine fibrous filling, as cut straw or chaff to augment their pliability for adjustment, easy fitting and easy service. So in the construction of this invention, the sweenys or tops of the after-wales 8 and the adjacent tops of the forewale or rim 9, both being the 90 parts particularly improved and combined with the new features of this invention, are stuffed with a modified fine fibrous filler, to facilitate the required adaptation and are of structure as follows: 95

Very short top portions 10 of the wales have the inner and outer walls disposed flatly together without fillings, to properly close these top ends and are secured by stitching as shown. The filling immediately below 100 these closed ends is a selected long uncut fibrous material 11. It is first inserted in meager quantity and retains its position,

ranged endwise up and down, in these thin parts, of the cavities that are stuffed, where a sparse quantity of cut or short fibered 5 filler has a tendency to settle or shift downwardly, if it is not too solidly packed. As the stuffing progresses, filling the cavity from the top downwardly, the quantity of filling is increased by the intermixture of the cut or short material until such size of 10 cavity is approached as will carry the short or cut material 12 used alone, and stand up to the service required and give the desired flexibility of the sweenys. The change from long to fine or short filling is made gradually 15 and the two thoroughly incorporated so that no appearance of splice will be developed on the exterior or in the completed collar by any subsequent hard service.

A combined housing-plate and adjusting 20 overlap or extension plate 13 is made rectangularly oblong of two thicknesses of heavy pliable but firm quality of harness leather. The inner layer 14 and outer layer 15 are of 25 equal size, slightly rounded at the corners and sewed together by a seam adjacent to the corresponding edges clear around. In 30 width this plate is not less than the width of the closed top ends of the sides of the collar, to one of which top ends one end 16 of the plate is attached by overlapping said plate end onto the outside thereof and then 35 stitched or riveted therethrough, as shown. At the opposite or free end of the plate the top end of a long heavy billet 17 is inserted 40 between the layers of the plate toward the back edge thereof and secured by the seam uniting the layers of the plate and by riveting. Below on the outside of the adjacent 45 side after-wale a suitable buckle 18 with tuck loop is attached to receive and secure the billet. When this billet is buckled down to its farthest extent, as shown in Figs. 4, 5 and 7, bringing the opposite closed side 50 tops together, the collar is fastened at its position of smallest adjustment; and may be let out to any desired larger size within the range of the overlap of the free end of the 55 adjusting housing plate onto the adjacent overlapped collar side. At any adjustment of the heavy laminate plate readily bends to form a new vertex of the arched top, and in so bending assumes or forms a straight transverse section, as shown in Fig. 2, of sufficient rigidity to resist the down draft of the top hame coupling thereon.

An upstanding heavy ledge 19, disposed longitudinally along a central portion of the front edge of the housing plate, prevents the 60 hame strap or other hame coupling from shifting forward off of the housing and assists the hames to retain the very pliable top parts of the sides of the collar in correct vertical alinement when the collar is let 65 out to its largest size. This ledge is made

by inserting the two thick strips of leather 20 between the front edges of the layers 14 and 15, as shown in Fig. 2, and stitching through them when the layers are seamed together. When the completed plate is bent 70 in adjustment it is obvious that the outer layer more readily stretches and yields to this added thickness and forms the desired outside ledge, of sufficient length for any adjustment and in position as shown in Figs. 75 1, 2, 3 and 4. To further support and stay the top I use an ordinary stiff pressed-leather chafe or neck-pad 21, having a transverse metal reinforcing plate 22 with regular attaching straps 23; one of these straps is inserted 80 through the flat loop-strip 24 to retain the pad when the top of the collar is opened by unbuckling the large billet 17; said loop-strip being fastened to the outer surface of the after-wale carrying the attached end of the housing plate, in the usual manner of applying such chafe pads.

In operation:—It is obvious that the heavy laminated extension plate is resistant to edgewise strains that occur in service and 90 tend to distort the flexible adjustably lengthened tops of the sides.

That the new top or arch vertex, formed by the flatwise longitudinal bend of the plate for any new size adjustment, and retained 95 thus bent by the lateral compression of the applied hames, becomes a vaulted top made sufficiently rigid by this longitudinal bending and lateral hame compression, to preserve the desired shape and form of the connected sides and top of the collar.

And, that the billeted end of the extension plate when slid downwardly toward the buckle, for smaller adjustment of the collar, will, thus longitudinally straightened, 105 readily bend transversely and be forced into the outer groove of the collar between the rim and the after-wale by the applied hame, rendering this open side as stable for service as the opposite permanently-connected 110 side and end.

It will be understood that the required adjustments of the size of the collar are infrequent: only occurring, when the collar is first applied for service, when hard work 115 or disorder has reduced the animal's flesh, a young horse has outgrown his first collar fitting, or when it becomes expedient to fit the collar on another animal. In the intervening periods of service, the extension 120 plate becomes set to its fitted shape of top arch and transverse bend of the removable end into the outer groove of the collar, and always goes back to its firm easy-fitting position, each time the collar is reapplied after 12 being opened for removal from the animal's neck. And, as at all points of adjustment the ends of the plate overlap the top ends of the collar sides, it serves perfectly as a housing shielding the top of the collar and 13

inclosed neck of the animal from rain or snow.

I claim:

1. An adjustable open top horse collar, comprising integral flexible throat and sides, a laminate connecting plate of firm heavy harness leather stitched together flatwise attached to the top of one collar side to bend flatwise to form a substantially rigid arch across the open top and to overlap the opposite collar side, narrow laminæ added to form an upstanding ledge on the front edge of said connecting plate, a long billet on the free end toward the back edge of said connecting plate, and a buckle on the outside of the after-wale of the adjacent collar side to engage said billet.
2. An adjustable open top horse collar, comprising integral throat and flexible-topped sides, an oblong rectangular connecting plate composed of two thicknesses of firm heavy harness leather fastened together, one end of said plate fastened to the top end of one of the collar sides, adapted to bend flatwise to form a substantially rigid arch to close the open top of the collar and overlap the opposite collar side, additional thickness of leather fastened between the front edges of the leathers composing the connecting plate to bend the top layer to form an upstanding ledge on said arch in the plane of the rim of the collar, and

means to releasably connect the free end of said plate at different selective heights on the overlapped sides.

35

3. An adjustable open top horse collar, comprising wales having short top end portions of their inner and outer walls closed flatly together, meager quantities of long fibrous filling adjacent to the closed ends 40 of said wales, intermixed lower down with a progressively increased quantity of short or cut fibrous filling and finally omitting the long filling, to form collar sides of increased pliability toward their top ends, in 45 combination with an oblong laminate closing plate of firm harness leather having one end fastened exteriorly on the closed top end of one of the collar sides and adapted to be bent longitudinally flatwise, at any 50 intermediate point in its length, to form a substantially rigid arch to close the top of the collar and the less bent free end portion of said plate, when longer than required in the top adjustment adapted to be gripped 55 and bent transversely into the outer groove of the overlapped collar side by the applied harness-hame, and means connected to releasably fasten said free end of the closing plate at selective heights on said overlapped 60 collar side.

In testimony whereof I hereunto affix my signature.

CHARLES ROSS.
